UNITED STATES PATENT OFFICE.

CLYDE COLEMAN, OF CHICAGO, ILLINOIS, ASSIGNOR TO THE BANKERS ELECTRIC PROTECTIVE COMPANY, OF SAME PLACE.

BURGLAR-ALARM SYSTEM.

SPECIFICATION forming part of Letters Patent No. 667,115, dated January 29, 1901.

Application filed July 12, 1898. Serial No. 685,801. (No model.)

To all whom it may concern:

Be it known that I, CLYDE COLEMAN, a citizen of the United States of America, and a resident of Chicago, in the county of Cook and State of Illinois, have invented certain new and useful Improvements in Burglar-Alarm Systems, of which the following is a specification.

The present invention relates to an electric protective system against burglars, and more particularly to that class of such systems in which the alarm mechanism is located within a guarded structure, an example of which may be found in Reissue Letters Patent No. 11,626, to Coleman, Deane, and Donnell, dated August 17, 1897.

The objects of the present improvements are as follows: first, to provide a simple, durable, and effective means for preventing access to the alarm mechanism through the sound outlet or passage of the alarm structure with a purpose of disabling or the destruction of such alarm mechanism, and which means in the simpler form of the present invention involves an electrical barrier interposed between the mechanical barrier and the alarm mechanism and in the more advanced form of the present invention the interposition of such electrical barrier between a duplicate arrangement of the mechanical barriers in front of the alarm mechanism, so that the innermost mechanical barrier must be passed after the destruction of the electrical barrier before the alarm mechanism can be reached, thus affording an interval of time in which such alarm mechanism will be operative before it can be reached through such innermost mechanical barrier, all as will hereinafter more fully appear, and be more particularly pointed out in the claims; second, to provide a simple and efficient form of electrical barrier for such guarded structures for alarms and other allied uses that is very sensitive to any unauthorized disturbance in its structure or the structures adjacent thereto; third, to provide in connection with such alarm mechanism and its guarded inclosing structure, aperured for the emission of sound, means for sounding an alarm when an attempt is made to muffle the alarm mechanism by the introduction of a fluid or mobile mass

into the interior of the guarded structure inclosing the alarm mechanism; fourth, to provide, in connection with the entrance door or cover of the guarded structure of an alarm mechanism and in connection with the series of independent fastenings, individual means for giving an alarm when any one of the fastenings is tampered with. I attain such objects by the construction and arrangement of parts, substantially as shown in the accompanying drawings, in which—

Figure 1 is a diagrammatic view illustrating an electrical protective system against burglars and illustrating the location and connection of the present improvements; Fig. 2, a longitudinal sectional elevation of the guarded structure for the alarm mechanism, illustrating the general arrangement of the present improvements; Fig. 3, a transverse sectional elevation of the same on line $x-x$, Fig. 2; Fig. 4, an enlarged detail sectional elevation of the fastening-means for the door of such guarded alarm structure and the circuit-breaking means connected with such fastening means; Fig. 5, an enlarged sectional elevation of the slatted type of electrical barrier of the present invention; Figs. 6, 7, 8, 9, 10, 11, and 12, enlarged detail sections illustrating various arrangements of the electrical conductors in connection with a frangible support; Fig. 13, an elevation of an ordinary frangible electrical barrier to illustrate the usual means employed to baffle the same; Fig. 14, a detail elevation of the duplex type of apertured-plate electrical barrier of the present invention; Fig. 15, a transverse section of the same on line $x'-x'$, Fig. 14; Fig. 16, a detail sectional elevation of the circuit-breaker that is adapted to operate when an attempt is made to muffle the alarm mechanism by the introduction of a mobile or fluid filling.

Similar numerals of reference indicate like parts in the several views.

The general arrangement of the present improvements in the guarded alarm-station of an electric protective system against burglars is illustrated in the diagram view Fig. 1 of the drawings, as well as its arrangement in connection with the structure to be guarded, which arrangement is substantially similar

to that shown in the prior Reissue Patent No. 11,626, heretofore referred to. In such diagram view, A represents the guarded structure as set forth in such prior patent and 5 may be the building part of a building, apartment, safe, vault, or other substructure which it is desired to protect and which has its vulnerable points or parts protected by one or more electrical barriers 1, that are in circuit 10 with a main controlling electrical circuit 2, that controls a relay or responsive apparatus 3, which in turn controls the alarm mechanism 4 of the system either in a direct or indirect manner, as may be found most desirable.

15 The guarded alarm structure or station B, as in the aforesaid prior patent, comprises a suitable metallic casing 5, provided with an entrance door or cover 6, and an apertured 20 side or wall 7 for the outward passage or escape of the sound produced by the alarm mechanism 4 contained within such casing. The casing 5 has its various walls protected by one or more electrical protective linings 25 or barriers 8, and, as in the former patent, contains the alarm mechanism 4, the battery for operating said alarm mechanism, the relay or responsive apparatus 3 for controlling the alarm mechanism, as well as the series of 30 circuit-breakers hereinafter described. The apertured side or wall 7 of the casing constitutes a mechanical barrier to prevent the entrance through or between the same of a tool to disable the alarm mechanism, and, as in 35 the said prior patent, is formed by any usual and suitable arrangement of slats, bars, or perforated plates that will afford such protection and yet admit of a ready outward passage of the sound from the alarm mechanism. 40 Such apertured wall or outer mechanical barrier 7 is illustrated in Fig. 2 as consisting of a series of superimposed angle-bars having a slightly-separated relation to form the necessary outlet-passages for the sound, and, as 45 mentioned above, any other equivalent construction of such mechanical barrier may be employed—as, for instance, two or more perforated plates, the perforations of which are staggered or alternated with relation to each other or an inclined or louver arrangement of 50 flat strips, as illustrated in Fig. 2, in the construction of the inner or secondary mechanical barrier 9 of the present invention. In the present invention the mechanical barriers 55 7 and 9 have a separated relation, and in the space between the same is arranged an apertured electrical barrier 10, of any suitable construction, with the insulated conductors thereof in circuit with a relay or responsive apparatus, such as 3, of the alarm mechanism or other equivalent means for releasing the alarm mechanism. Another part of the present invention involves the formation of 60 such apertured electrical barrier of an easily-frangible nature, and to this end the base or supporting portion 10 for the electrical conductors is formed of glass, porcelain, or other

analogous frangible material, either in the form of a series of bars or slats 12, as shown in Figs. 2, 3, 5, 6, 7, 8, 9, 10, 11, and 12, and 70 which are preferably staggered or alternated with relation to each other when assembled to constitute an electrical barrier, as illustrated in Figs. 2 and 5, or in the form of a series of perforated plates 13, the apertures or 75 perforations of which are staggered or alternated with relation to each other, as illustrated in Figs. 14 and 15. It is within the province of this part of the present invention to form the electrical conductors 14 of ordinary insulated wires secured to the back of the frangible support in a parallel arrangement, as shown in Fig. 8, or in the form of two parallel conductors placed between two sections of such frangible supporting-base, 85 as illustrated in Fig. 10. With a view, however, to achieve added security in this connection the present invention involves an improved arrangement of such electrical conductors in a closely adjacent and superimposed condition, one back of the other, upon an inner face of the frangible supporting-base, either by being secured to the back of the supporting-base 10, as illustrated in Figs. 5 and 6, or inclosed within sections of the 90 base, as illustrated in Figs. 7 and 9, or inclosed within a tubular form of such base, as 95 illustrated in Figs. 11 and 12. In either case the conductors are in the form of flattened strips or plates 14' of metal, usually tin-foil, 100 separated by strips 15 of insulating material, as shown.

With such construction as above described any attempt either to pass through the conductors by means of a drill or other tool or 105 to bridge over and cut out the main portion of such electrical conductors upon the barrier will cause the two superimposed and closely adjacent conductors of such improved arrangement to be brought in circuit with 110 each other, and by the disturbance set up in the electrical circuit or circuits of the system will cause the responsive apparatus to act and sound the alarm apparatus.

The arrangement of the conductors as above 115 set forth is especially adapted for use in connection with that class of alarm systems in which circuits of different or varying potentials are employed, in that the connection or crossing of the circuits above set forth will 120 so disturb such circuits as to cause the responsive appliance to act and release the alarm mechanism to sound an alarm.

The present improved arrangement of conductors obviates marked defects existing in 125 the ordinary arrangement of the single conductor heretofore used as an electrical protection for windows by being secured upon the inner surface of the window-glass and which was capable of being easily baffled in 130 manner illustrated in Fig. 13, in that by means of small holes 16, drilled in the glass, a bridge conductor 17 (shown in dotted lines) could be used to connect two adjacent por-

tions of the conductor together, and thus short-circuit the same, leaving the main portion of the protective conductor upon the surface of the glass in a cut-out or dormant condition, so that by a fracture and removal of such main portion of the glass an unauthorized entrance into the building could be effected without an alarm being given. With the present improved arrangement of the conductors, as heretofore described, no such attempt to short-circuit or bridge over would be successful.

Another part of the present invention consists in including the metal of the inclosing casing of the alarm structure in the electric circuit of the system, so that when it is brought into electrical connection with an adjacent electric lining by means of a drill or other tool a disturbance of the circuit will be set up to cause the alarm to sound, and to this end the electric lining 18, of any usual and approved construction, will have an arrangement closely adjacent to the metal walls of such casing, but insulated therefrom by means of a suitable insulation 19, as clearly illustrated in Fig. 4, in which the insulated electric lining 18 is arranged between the main outer casing 5 and a supplementary inner casing or lining 20, the entrance-door 6 having a similar construction, as shown in said Fig. 4.

Another part of the present invention consists in the provision in the lower portion of the guarded alarm station or casing 5 of an automatically-operating circuit-controlling mechanism that is adapted to operate upon an attempt being made to muffle the alarm mechanism by the introduction through the sound-aperture thereof of a fluid or mobile filling of water, sand, or the like. In the form of such apparatus shown in Figs. 2 and 16 of the drawings as illustrating this part of the present invention 21 is a fulcrumed beam carrying on one end a buoyant or other float 22 and at the opposite end a circuit-controlling device 23, that preferably consists of a glass chamber 24, containing a shifting metal body 25, preferably mercury, and provided with a pair of insulated terminals 26 27, extending in through the walls of such chamber, as shown. With this construction and with the parts in a normal position, as indicated in Fig. 16, the mercury will connect the two terminals 26 and 27 together to complete the circuit, when, however, by the introduction of a liquid or mobile mass the float 22 is caused to rise and the chamber 24 to be correspondingly depressed until the mercury flows away from the terminals 26 27, breaking the circuit and causing the alarm mechanism to sound an alarm. The chamber 24, containing the moving body of mercury, is made of glass mainly for the reason that owing to its fragile nature it is likely to be broken when the apparatus is tampered with and thus spill the mercury and break the circuit to sound an alarm.

Another part of the present invention consists in the provision, in connection with the series of independent fastenings for the door or cover 6 of the alarm-casing 5, of individual circuit-controlling devices that are adapted to control an electric circuit and give an alarm when any one of such fastenings is tampered with. In the form of apparatus shown in Fig. 4 of the drawing as illustrating this part of the present invention 28 represents one of a series of screw-bolts by which the door or cover 6 is secured to the alarm-casing 5. In axial alinement with such bolts is a spring-plunger 29, that is adapted to be moved longitudinally by the screw-bolt 28 as the same is screwed into place. The housing 30 for such plunger carries two contact points or terminals 31 and 32, between which the lower metallic end of the plunger is forced to electrically connect said terminals together when said plunger is pushed downward by the screw-bolt. With this construction when one of the bolts 28 is tampered with by an attempt to unscrew or otherwise remove the same the lower end of the spring-plunger 29 will move away from between the terminals to break the circuit and cause the alarm mechanism to sound an alarm.

Having thus fully described my said invention, what I claim as new, and desire to secure by Letters Patent, is—

1. In an electrical protective system, the combination of an electrically-protected structure, an electrically-protected alarm structure, an alarm mechanism arranged therein and controlled by the main protective circuit, an electrical barrier for said alarm structure consisting of a series of conductors, a supporting-base for said conductors provided with apertures, and a mechanical barrier adjacent to said electrical barrier also provided with apertures, substantially as set forth.
2. In an electrical protective system, the combination of an electrically-protected structure, an electrically-protected alarm structure, an alarm mechanism arranged therein and controlled by the main protective circuit, an electrical barrier for said alarm structure consisting of a series of conductors, a supporting-base for said conductors provided with apertures, and a mechanical barrier also provided with apertures and so arranged as to prevent speedy access to the alarm mechanism after the destruction of the electrical barrier, substantially as set forth.
3. In an electrical protective system, the combination of an electrically-protected structure, an electrically-protected alarm structure, an alarm mechanism arranged therein and controlled by the main protective circuit, an electrical barrier for said alarm structure, consisting of a series of conductors, a supporting-base for said conductors provided with apertures and a series of mechanical barriers also provided with apertures, the

electrical barrier being interposed between such mechanical barriers, substantially as set forth.

4. In an electrical protective system, the combination of an electrically - protected structure, an electrically - protected alarm structure, an alarm mechanism arranged therein and controlled by the main protective circuit, an electrical barrier for said alarm structure consisting of a series of conductors, and a supporting-base for said conductors formed of frangible material and provided with apertures, substantially as set forth.

5. In an electrical protective system, the combination of an electrically - protected structure, an electrically - protected alarm structure, an alarm mechanism arranged therein and controlled by the main protective circuit, an electrical barrier for said alarm structure consisting of a series of conductors, a supporting-base for said conductors formed of frangible material and provided with apertures, and a mechanical barrier adjacent to said electrical barrier also provided with apertures, substantially as set forth.

25 6. In an electrical protective system, the combination of an electrically - protected structure, an electrically - protected alarm structure, an alarm mechanism arranged therein and controlled by the main protective circuit, an electrical barrier for said alarm structure, consisting of a series of conductors, a supporting-base for said conductors formed of a frangible material and provided with apertures, and a mechanical barrier also provided with apertures and so arranged as to prevent speedy access to the alarm mechanism after the destruction of the electrical barrier, substantially as set forth.

40 7. In an electrical protective system, the combination of an electrically - protected structure, an electrically - protected alarm structure, an alarm mechanism arranged therein and controlled by the main protective circuit, an electrical barrier for said alarm structure, consisting of a series of conductors, a supporting-base for said conductors formed of a frangible material and provided with apertures, and a series of mechanical barriers also provided with apertures, the electrical barrier being interposed between such mechanical barriers, substantially as set forth.

50 8. In an electrical protective system, the combination of an electrically - protected structure, an electrically - protected alarm structure, an alarm mechanism arranged therein and controlled by the main protective circuit, an electrical barrier for said alarm structure, consisting of a series of conductors, arranged one back of the other in close and insulated relation, and a supporting-base for said conductors provided with apertures, substantially as set forth.

60 9. In an electrical protective system, the combination of an electrically - protected structure, an electrically - protected alarm structure, an alarm mechanism arranged

therein and controlled by the main protective circuit, an electrical barrier for said alarm structure, consisting of a series of conductors arranged one back of the other in close and insulated relation, and a supporting-base for said conductors formed of frangible material and provided with apertures, substantially as set forth.

75 10. In an electrical protective system, the combination of an electrically - protected structure, an electrically - protected alarm structure, an alarm mechanism arranged therein and controlled by the main protective circuit, an electrical barrier for said alarm structure consisting of a series of conductors, and a supporting-base for said conductors formed by two sections or portions of frangible material between which the conductors are arranged and provided with apertures, substantially as set forth.

11. In an electrical protective system, the combination of an electrically - protected structure, an electrically - protected alarm structure, an alarm mechanism arranged therein and controlled by the main protective circuit, an electrical barrier for said alarm structure consisting of a series of conductors, arranged one back of the other in close and insulated relation, and a supporting-base for such conductors formed of two sections or portions of frangible material between which the conductors are arranged and provided with apertures, substantially as set forth.

90 12. In an electrical protective system, the combination of an electrically - protected structure, an electrically - protected alarm structure, an alarm mechanism arranged therein, and controlled by the main protective circuit, a door or cover for said alarm structure, a fastening device therefor, and a circuit-controlling device actuated by the movement of said fastening device, substantially as set forth.

95 13. In an electrical protective system, the combination of an electrically - protected structure, an electrically - protected alarm structure, an alarm mechanism arranged therein, and controlled by the main protective circuit, a door or cover for said alarm structure, a series of fastening devices therefor, and a series of individual circuit-controlling devices actuated by the movement of said fastening devices, substantially as set forth.

105 14. In an electrical protective system, the combination of an electrically - protected structure, an electrically - protected alarm structure, an alarm mechanism arranged therein and controlled by the main protective circuit, a door or cover for said alarm structure, a screw-bolt fastening device therefor, and a circuit-controlling device actuated by the movement of the screw-bolt, substantially as set forth.

110 15. In an electrical protective system, the combination of an electrically - protected structure, an electrically - protected alarm structure, an alarm mechanism arranged

therein and controlled by the main protective circuit, a door or cover for said alarm structure, a series of screw-bolt fastening devices therefor, and a series of individual controlling devices actuated by the movement of the screw-bolts, substantially as set forth.

16. In an electrical protective system, the combination of an electrically-protected structure, an electrically-protected alarm structure, an alarm mechanism arranged therein, and controlled by the main protective circuit, and a circuit-controlling device arranged in the interior of the alarm structure and adapted to operate upon the introduction of a mobile body into the interior of such structure, the same comprising a balance-lever, a float and a chamber at the respective ends of the lever, and a shifting metal body in the chamber adapted to make and break the electrical circuit, substantially as set forth.

17. In an electrical protective system, the combination of an electrically-protected structure, an electrically-protected alarm structure, an alarm mechanism arranged therein, and controlled by the main protective circuit, and a circuit-controlling device arranged in the interior of the alarm structure and adapted to operate upon the introduction of a mobile body into the interior of the structure, the same comprising a balance-lever, a float and a chamber of frangible material at the respective ends of the lever, and a shifting metal body in said chamber adapted to make and break the electrical circuit, substantially as set forth.

Signed by me at Chicago, Illinois, this 30th day of June, 1898.
